CLAIM

The ornamental design for a lid for a beverage container, as shown and described.

DESCRIPTION

FIG. 1 is a front perspective view of a lid for a beverage container showing our new design;

FIG. 2 is a bottom perspective view thereof;

FIG. 3 is a left side elevational view thereof;

FIG. 4 is a right side elevational view thereof;

FIG. 5 is a top view thereof;

FIG. 6 is a bottom view thereof; and,

FIG. 7 is a rear perspective view of the lid in its opened position in use.

The broken lines in the drawing depict portions of the lid for a beverage container that form no part of the claimed design.

1 Claim, 6 Drawing Sheets
